UNITED STATES PATENT OFFICE.

EDWARD G. BUDD, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

SEATING.

No. 884,710.

Specification of Letters Patent.

Patented April 14, 1908.

Application filed February 15, 1907. Serial No. 357,476.

To all whom it may concern:

Be it known that I, EDWARD G. BUDD, a citizen of the United States, residing at Philadelphia, in the county of Philadelphia and 5 State of Pennsylvania, have invented a certain new and useful Improvement in Seating, of which the following is a description.

This invention relates to seating for various uses and particularly for use in the 10 manufacture of seats of the type commonly employed in railway cars.

The object of the invention is to provide a seating, the parts of which are all, or substantially all, made of metal and which is 15 therefore fireproof. This object is obtained by the employment of a metallic frame and a covering stretched over and secured to the frame, this covering being formed of substantially flat, metallic strands, closely interwoven. 20 Such a covering, I have found, possesses the requisite flexibility, wears well, can be manufactured at small cost, and presents an attractive appearance, in addition to being fireproof. In the construction of 25 such a metallic covering, it is desirable to use strands of metal which is rather soft and pliable in order to facilitate the operation of weaving, of carrying the covering around and under the members of the frame and of 30 folding the covering at the corners of the frame. By reason of the softness and pliability of these metal strands, the usual springs for yieldingly supporting the covering of the seating might not furnish a sufficient 35 yielding support for the covering at all points on its surface and therefore the covering, after being depressed at certain points, might not be returned to its original position, presenting a smooth resilient surface. To 40 guard against this, I provide a means, additional to the usual spiral springs, for yieldingly supporting the covering, this means consisting of a plurality of strips of spring-metal underlying the woven metallic covering. 45 These strips may be woven into the covering on the under side thereof at intervals across it in one or both directions, or they may be woven separately to form an open mesh structure which lies directly under but 50 is separate from the covering. These strips of spring-metal need only be of such size as to underlie the central portion or top surface of the seating, but, if desired, some or all of the strips may extend over and down along 55 the outer sides of the frame members. Those

strips adjacent to the edges of the covering, however, should not extend out to the edges for the reason that it is usual to make folds in the covering at the corners of the frame and the spring-metal strips would make such 60 folding more difficult.

The preferred embodiment of the invention is illustrated in the accompanying drawings, in which

Figure 1 is a sectional elevation of a cushion 65 such as may be used as the seat-cushion of a car-seat; Fig. 2 is a detail view, in plan, of a portion of the covering on an enlarged scale; and Fig. 3 is a section on line 3—3 of Fig. 2.

Referring to these drawings, the cushion 70 consists of a rectangular frame formed of four sheet-metal frame-members 1, secured together at their ends. Each of these frame-members has an inwardly curled flange 2 at its upper edge, an inwardly extending flange 75 3 at its lower edge, and a curled portion 4 at the edge of the flange 3. Extending across between opposite side members of the frame and secured at their ends thereto, are a plurality of channeled metallic slats 5, each supporting a plurality of spiral springs 6. Each row of springs 6 supports on the upper ends thereof a flat metallic spring 7, the ends of which are turned down alongside the frame-members 1. The metallic covering 8 is 85 drawn over the flat springs 7 and down along the members 1 of the frame, the edges thereof being carried over the flanges 3 and around the curled portions 4. Metallic clamping 90 members 9 are gripped around the covering and the curled portions 4 to secure the edges of the covering to the frame.

The covering consists of a plurality of strands 10 and 11 of soft, pliable metal, closely interwoven. Any suitable weave of 95 the strands may be employed, as for instance the square weave shown in Fig. 2 or a twill weave. In the drawings, I have shown the strips 12 of spring-metal interwoven with the strands of the covering and this is the construction I prefer to use, but, if desired, the strips may be separate from the covering. In either case, the strips 12 are on the under side of the covering and hence do not show from the exterior of the cushion. In the construction illustrated, each of the strips 12 directly underlies, and is woven with, a strand of the covering. The intervals between the strips 12 may be varied as desired but preferably the strips are about an inch apart. 110

To secure the results for which the strips 12 are provided, it is only necessary that they extend across the central portion of the covering, that forming the top of the cushion. 5 They may, however, be of such length that their ends extend down along the frame members 1 a short distance as indicated by the dotted lines 13 in Fig. 1, or they may extend to the edge of the covering. Preferably 10 the strips 12 lying adjacent to the members 1 of the frame are much shorter, so that they do not extend down along the members of the frame at all, for the reason that it is necessary to fold the covering at each of the 15 corners of the cushion so as to make a neat structure and the strips being far less pliable than the strands 10 and 11 would make the operation of folding the covering more difficult.

20 The strands 10 and 11 are preferably flat strips, as indicated by the sectional view in Fig. 3, but if desired the outer surface of these strips may be somewhat convex and the covering may have a coating of an in- 25 combustible or other enamel applied to the outer face thereof. The strips 12 are also substantially flat and preferably of the same width as the strands 10 and 11. It will be seen that by this construction, the cushion 30 is of metal throughout, the covering is flexible and after the covering has been depressed it will be forced back to its original position by the strips 12, since the latter are made of spring-metal. The springs 6 and 7 form a 35 yielding support for the covering of the cushion, but might not be sufficient to prevent the covering from being dented and taking a set in a shape other than that desired, on account of the spaces between them, but such 40 denting and setting of the strands 10 and 11 is effectually prevented by the strips 12.

Having now described my invention, what I claim as new therein and desire to secure by Letters Patent is as follows:—

45 1. The combination of a metallic frame, slats extending across the same, spiral springs mounted upon the frame, flat metallic springs supported upon the upper ends of said spiral springs, a covering consisting of flattened, pliable, metallic strands closely 50 interwoven extending over said frame and secured at its edges thereto, said covering forming the surface material of the cushion and being yieldingly sustained by said 55 springs, and a plurality of strips of spring-metal interposed between said flat springs and said covering, substantially as set forth.

60 2. The combination of a metallic frame, metallic slats extending across the same, spiral springs mounted on said slats, flat metallic springs supported upon the upper ends of said spiral springs, a covering consisting of flattened, pliable, metallic strands closely 65 interwoven extending over said frame and secured at its edges thereto, said cover-

ing forming the surface material of the cushion and being yieldingly sustained by said springs, and a network of spring-metal strips between said flat springs and said covering, substantially as set forth.

3. The combination of a metallic frame, slats extending across the same, spiral springs mounted upon the frame, flat metallic springs supported upon the upper ends of said spiral springs, a covering consisting of flattened, pliable, metallic strands closely interwoven extending over said frame and secured at its edges thereto, said covering forming the surface material of the cushion and being yieldingly sustained by said springs, and a plurality of strips of spring-metal interwoven with said strands, substantially as set forth. 75

4. In seating, a frame, a covering secured over the frame formed of flattened pliable, 85 metallic strands closely interwoven, said covering forming the surface material of the seating, and means interwoven with said strands for making the central portion of the covering resilient, substantially as set forth. 90

5. In seating, the combination of a metallic frame, a covering formed of flattened, pliable, metallic strands closely interwoven extending over said frame and folded about the edges thereof, said covering forming the 95 surface material of the seating, and flat metallic strips interwoven with said strands for stiffening the portion of the covering lying between the members of the frame, substantially as set forth.

6. The combination of a metallic frame, slats extending across the same, spiral springs mounted upon the frame, flat metallic springs supported upon the upper ends of said spiral springs, a covering consisting of flattened, pliable, metallic strands closely 105 interwoven extending over said frame and secured at its edges thereto, said covering forming the surface material of the cushion and being yieldingly sustained by said 110 springs, and a network of spring-metal strips between said flat springs and said covering, said covering being of greater size than said network, substantially as set forth.

7. In seating, a covering consisting of flattened, pliable, metallic strands closely interwoven, and a plurality of flat, spring-metal strips interwoven with said strands for making the covering resilient, substantially as set forth. 115

8. In seating, a covering formed of flattened metallic strands closely interwoven and a plurality of strips of spring-metal interwoven with said strands, each strip lying parallel to and in engagement with one of 125 said strands, substantially as set forth.

9. In seating, the combination of a metallic frame, a covering formed of woven metallic strands extending over said frame and secured thereto, and a plurality of strips of 130

spring-metal interwoven with said strands each directly underlying one of said strands, substantially as set forth.

10. In seating, a covering formed of substantially flat, metallic strands closely interwoven and a plurality of substantially flat strips of spring-metal interwoven with said strands at intervals across the covering, each strip directly underlying one of said strands, substantially as set forth.

11. In seating, the combination of a metallic frame, a covering formed of flattened metallic strands closely interwoven extending across said frame and over the outer sides of the members thereof and folded about and secured to said members, and a plurality of strips of flat spring-metal interwoven with said strands and crossing each other at substantially a right angle, the ends of each of said strips extending along the outer sides of opposite members of said frame, substantially as set forth.

12. In seating, the combination of a rectangular frame, a covering formed of substantially flat, metallic strands closely interwoven extending across said frame and over the outer sides of the members thereof and folded about said members, and a plurality of substantially flat strips of spring-metal interwoven with said strands at intervals across the covering and each directly underlying one of said strands, the strips lying in the central portion of the seating being longer than those adjacent to the members of the frame and having their ends bent

down along the outer sides of the members of the frame, substantially as set forth.

13. In seating, the combination of a metallic frame, a covering secured thereto consisting of flattened metallic strands closely interwoven, and a plurality of strips of flat spring-metal underlying said covering, the ends of said strips being free to move relatively to said frame and certain of said strips extending at an angle to and crossing other strips, substantially as set forth.

14. In seating, the combination of a metallic frame, a covering secured thereto consisting of flattened metallic strands closely interwoven, and a plurality of interwoven strips of flat spring-metal underlying said covering and free to move relatively to said frame at all points, substantially as set forth.

15. In seating, the combination of a metallic frame, a covering extending across said frame and over the sides thereof and secured at its edges thereto consisting of flattened metallic strands closely interwoven, and a plurality of strips of spring-metal underlying said covering, the strips crossing the central portion of the covering being longer than those adjacent to the edges thereof, substantially as set forth.

This specification signed and witnessed this 8th day of February, 1907.
